UNITED STATES PATENT OFFICE

ROY E. SHUNK, OF TOLEDO, OHIO, ASSIGNOR TO THE AMERICAN FLOOR SURFACING MACHINE COMPANY, OF TOLEDO, OHIO

HANDLE SWITCH CONSTRUCTION

Application filed October 24, 1928. Serial No. 314,691.

This invention has reference to an improved electric switch and complementary handle structure for domestic vacuum cleaners and the like and particularly for a new household waxer manufactured and distributed by the American Floor Surfacing Machine Co., the assignee of this invention.

In attempting to fulfill the needs of economic and expeditious production of this portable waxer, I have discovered an arrangement of switch assembly, "pistol" hand-grip and operating trigger which makes for greater compactness and convenient structure, minimizes labor, saves time, materially reduces cost of manufacture and sale, and increases quantity output, and thereby functions to provide a valuable and novel contribution to the art.

I am aware of the fact that it is not new to embody a switch and control or operating member in the handle construction of vacuum cleaners and the like. It follows therefore that my principal aim is to provide a structure which is believed to be a mechanical achievement beyond known prior art devices, a structure which is practicable, modern in general arrangement, highly efficient in performance, and susceptible of fulfilling the requirements of an invention of this class in a positive and dependable manner.

In the drawing:

Figure 1 is a fragmentary side view in elevation showing the external configuration and arrangement.

Figure 2 is a view based on Figure 1, with portions broken away and shown in section to disclose the internal mechanism.

Figure 3 is a top view of Figure 2 with portions broken away and in section, to show the construction and relationship of certain other details.

Figure 4 is a perspective view of one of the details.

Figure 5 is a view in section and elevation showing the method of assembling the details.

Figure 6 is a sectional view taken approximately upon the plane of the line 6-6 of Figure 1.

Figure 7 is a perspective view showing the

manner in which the electric conductor is cut and bent to adapt it for use in connection with the improvement.

Figure 8 is a perspective view of the switch operating trigger or button,

Figure 9 is a sectional view through the movable spring circuit closing element.

Referring now to the drawings by reference numerals it will be observed that 10 designates the upper end of a tubular handle such as is ordinarily provided for vacuum cleaners, floor waxes and the like. It is to be noted however that the customary coiled spring near the upper open end is omitted and an opening is formed in one side in which a rubber ring like bushing 11 is placed. One branch or end portion 12 of the electric conductor 13 extends through this and the other branch or stretch 14 extends down through the tube where it is connected with the electric motor (not shown).

The conductor is bent upon itself and a protective casing is slit at the bend to dispose wired ends 15 and 16 connected with the circuit closing means.

Considering Figure 5 it will be observed that the circuit closing means embodies a frame 17 including a metal portion 18 and a fiber portion 19, the fiber portion being constructed as shown in cross section in Figure 3 to provide a track. There is mounted upon this fiber portion an outstanding contact and wire anchoring clips 20 and 21 in which the wire ends 15 and 16 are respectively connected.

As shown plainly in Figures 2 and 5, this frame constitutes a carrier for a floating circuit closing device generally designated by the reference character 22. This device is preferably made up of a pair of spaced parallel plates 23 of the design shown in Figure 4 this plate having a notched head 24 at one end and a slot 25 at the opposite end.

A coil spring 26 surrounds the plates and holds them together and the notched head engages a contact roller 27 which is movable along the track formed by the member 19 in order that it may bridge the stationary contact clips 20 when in one position to start

the motor and move to a neutral position as shown in Figure 5 to stop it.

Directing attention now more particularly to Figure 2 it will be seen that novel control and operating means is provided for actuating this spring circuit closer or movable contact device. I first direct attention to the 5 slidable trigger 28 in the form of an elongated slotted block composed of insulation material. Pivoted in the slot as at 29 is a 10 wing-like actuator 30.

The wings act as stops and carry a centralized 15 extension 31 which cooperates with a pin slidably received in the slot 25 of the two plates 23. This wing-like actuator is pivoted at 32 in the metal portion of the frame. Thus, I provide a novel pin and slot connection between the actuator 30 and the floating circuit 20 closing device 22.

25 The parts 17, 20, 21, 22, 28 and 30 provide a novel switch assembly or units. This arrangement is advantageous in that it permits the units to be pre-made so that it can be easily slipped into the tubular handle 10 when desired.

Incidentally I call attention to sleeve 33 of 30 insulation material which surrounds the assembly as shown in Figure 5. Closely associated with the tubular handle and the switch assembly is the pistol grip 34 which is constructed of insulation material.

The small end of this grip is bifurcated in the furcations designated at 35. At the inner ends of the furcations is a counter recess 36 forming a pocket for reception of the 35 slidable trigger 28.

The construction is assembled as follows. The free end of the stretch 14 of the conductor 40 13 must first pass through the rubber bushing 11 and out through the open end of the metal tube 10. The cable is then bent upon itself and the casing is split and the wire cut as shown in Figure 7 in order to expose the wire ends 15 and 16. This enables the 45 mechanic to readily connect the wire end with the clip 20 while the switch assembly is in spaced relation from the end of the tubular handle.

The end of the switch assembly is brought 50 into position shown in Figure 5 and shoved into the handle and wires 12 and 14 drawn to take up slack. Then the pistol grip is put into position by telescoping the furcations into the insulation sleeve 33 where they straddle the switch assembly and dispose the trigger 28 in the pocket 36. Finally the retaining screws 37 are put in position to hold the structure thus assembled.

The advantage of this arrangement is primarily an economic one. It has been found that this method of assembly will eliminate practically all labor, will eliminate the customary metal cover plate and attaching plate, the protecting spring which is generally used 65 to retard the wearing through the insulation

of the power supply cord or line where it enters the middle portion of the tubular handle, as well as a goodly portion of the pistol grip material.

This economy when considered in connection with the overhead generally charged to manufacturing activities amounts to considerable when a large volume of production is in process. The grip is made of non-conducting material and is slotted or bifurcated 70 backward from the connecting end to receive the switch assembly.

The metal portion of the handle is well insulated from the switch by the cylindrical insulating sleeve which fits snugly in the tube 80 and tightly over the fiber handle and the switch control is different in form and utility than the control generally employed in switches and retains the switch from any foreign movement. The control extends above 85 and below the rearward point of the union between the metal tube and the pistol grip which are held together firmly by the laterally disposed retaining screw.

In conclusion it is thought that the structure herein shown and described is something which will supersede prior art structures, something which is practical and modern and which has been unequalled in the art. The distinguishing features will however be quite 95 apparent to persons skilled in the art to which the invention relates for which reasons a more detailed description is regarded unessential.

Having thus described my invention, what I claim as new is:

1. In a structure of the class described, a hollow tubular handle, a switch assembly in said handle, and a solid hand grip having a portion fitting telescopically in said handle and straddling said switch assembly to aid in holding the latter in place.

2. In a structure of the class described, a tubular handle, a switch assembly fitting into one end of the handle and including a 110 slidably mounted control trigger abutting the end of the handle, and a solid hand grip having a portion fitting into said handle and embracing said trigger.

3. In a structure of the class described, a tubular handle, a hand grip having a bifurcated end portion fitting telescopically into said handle, and a switch assembly including a control trigger confined between the furcations of said hand grip.

4. In a structure of the class described, a tubular handle, a solid pistol grip of insulation material bifurcated at its inner end to provide vertically disposed furcations, said furcations fitting telescopically into said handle, and a switch assembly including a mechanism carrier frame, and an elongated block like operating trigger pivotally connected to said frame and movable in a vertical direction at right angles to the longitudinal axis

of said handle, said frame and trigger being confined between said furcations.

5. In a structure of the class described, a hollow tubular handle provided adjacent one end and on one side with an opening for the passage of an electric current conductor cable, a rubber ring-like bushing fitted into said opening, a switch disposed in said handle, a solid hand grip having a bifurcated end fitting telescopically in said handle and embracing said switch, and a conductor cable extending through said bushing and into the tube and having its inner end portion bent upon itself to extend down through the tube, portions of the wire at said bend being cut and bared and connected with said switch.

10 6. In a structure of the class described, a tubular handle, a solid pistol grip of insulation material bifurcated at its inner end to provide vertically disposed furcations, said pistol grip having a vertically disposed pocket where the furcations merge with the body thereof, a switch assembly including a mechanism carrying frame and an elongated block-like operating trigger pivotally connected to said frame, said frame being straddled by said furcations and the trigger slidably confined in said pocket.

In testimony whereof I affix my signature.

ROY F. SHUNK.
